WINDOW CONSTRUCTION

Herman Mers, New York, N. Y.

Application November 24, 1945, Serial No. 630,611

7 Claims. (Cl. 20—49)

1

This invention relates to window construction. An object of this invention is to provide a window sash which may be slidably moved up and down, and which may be swung forwardly about its lower end to an inclined ventilating position, and which may also be swung all the way down to horizontal position to facilitate cleaning of the outside of the window sash.

Still another object of this invention is to provide a strong, durable and compact window construction of the character described which shall be relatively inexpensive to manufacture, easy to manipulate, and yet practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown various possible illustrative embodiments of this invention:

Fig. 1 is a partial front elevational view of a window construction embodying the invention;

Fig. 2 is a cross-sectional view taken on line 2—2 of Fig. 1;

Fig. 3 is a cross-sectional view taken on line 3—3 of Fig. 1;

Fig. 4 is a vertical sectional view through the open window sash in its horizontal position for cleansing, taken substantially on line 4—4 of Fig. 3, looking in the direction indicated by the arrows;

Fig. 5 is an enlarged cross-sectional view illustrating the pivot for the window sash;

Fig. 6 is a cross-sectional view taken on line 6—6 of Fig. 5;

Fig. 7 is a perspective view of one of the pivot pins;

Fig. 8 is an enlarged cross-sectional view taken on line 8—8 of Fig. 1; and

Fig. 9 is a partial side elevational view illustrating a modified construction; and Fig. 10 is a side elevational view of one of the pivoted levers.

Referring now in detail to the drawing, 10 designates a window construction embodying the invention. The same comprises a window frame 11 having vertical opposite side portions 12. Portions 12 are provided with spaced guide strips 13 forming a pair of oppositely disposed vertical grooves 14. Slidably mounted in the grooves 14 is a window structure 15.

2

The same comprises a pair of similar, symmetrically placed, vertical coextensive slide or slider members 16 on which is mounted a window 17. One slider member 16 slides in each one of the grooves 14 and is of angular transverse cross-section, being formed with a rear inwardly extending wall or flange 19 and a side forwardly extending wall or flange 20, thereby forming an angular vertical rabbet or notch 21 at the inner front side thereof. At the lower ends of the slider members 16 are rotatably mounted a pair of aligned, symmetrical, horizontal pivot pins 22. Each slider member 16 is formed with a hole or socket 23 to receive one end of the pivot pin. Each pivot pin 22 is formed at an intermediate portion thereof with a pair of milled flat faces 22a forming a web 22b therebetween of uniform thickness. The pins 22 project inwardly from the flanges 20 and project into the rabbets or notches 21. The window sash 17 is pivoted to the slider members 16 by means of said pivot pins 22. Said window sash 17 comprises a rectangular sash frame 25 having a bottom portion 26, a top portion 27, and side portions 28. The sash frame 25 carries the window pane 30. The side portions 28 are each formed at their outer surfaces and adjacent their rear surfaces with vertical grooves 31.

It will be noted that the side edges of the window sash 17 are received within the notches 21 of the slider members. The notches 21 form vertical chambers with the slider members for the purpose hereinafter appearing. The sash frame 25 is formed adjacent the lower end thereof with sockets 33 to receive the inner ends of the pins 22. The pins 22 may be fixed to the sash frame 25 as by set screws 25a or in any other suitable manner.

It will be noted that the pins 22 traverse the chambers 31. The height of the window sash 17 may be the same as the height of the slider members. When the window sash is in vertical position it may move up and down together with the slider members.

Means is provided to support the window sash 17 in inclined "ventilating" position or in horizontal "cleaning" position. To this end there is mounted on each pivot pin and within each chamber 31, a lever 40. The levers 40 are similar and symmetrically disposed to one another so that only one of said levers will be described. Each lever 40 is formed adjacent the lower end thereof with an inverted key hole-shaped slot or opening having a circular portion 42 and a

straight slotted portion 43 extending upwardly from the circular portion.

When the lever is pulled upwardly, said lever may rotate about the pin 22. When the lever is pushed downwardly the web 22b of the pin 22 will be received in the slotted portion 43 so as to prevent rotation of the lever relative to the pin and window. Each lever 40 is formed with a lower portion 44 adjacent the slider member and with an intermediate horizontal offset portion 45 and with an upper portion 46 parallel and offset from portion 44 and located adjacent the inner surface of the sash frame 25. The lever near the upper end of the window frame, is formed with an outwardly offset finger 47 which may be engaged or grasped by the fingers of the operator whereby the lever 40 may be pulled upwardly or pushed downwardly to engage or disengage the same, respectively of the pin 55 of the sash frame 25.

Said lever is furthermore formed adjacent its upper end with a bayonet slot 50. The slot 50 extends from the forward edge 51 of the lever and has an upwardly extending slotted portion 52.

Attached to the outer sides or outer edges and upper corner portions of the sash frame 25 are pins 55 adapted to enter the bayonet slots 50. When the levers 40 are pushed downwardly to engage slot 43 with web 22b, pin 55 will enter the longitudinal portion 52 of slot 50 to lock the window to the lever.

Means is provided to interconnect each lever 40 with its slider member 16. To this end there is pivoted to each slider member as at 60, a link 61. The link 61 is interpivoted by pivot 62 to a second link 63. Link 63 is pivoted as at 64 to lever portion 46. The links 61, 63 are so proportioned as to retain the levers at about 45° inclination. The pivotal point 64 may be somewhat above the offset 45 as shown in the drawing.

Means is further provided to interconnect the lever 40 to the window 17. To this end there is pivoted to each lever portions 44 as at 66, a link 67. The link 67 is interpivoted as by pivot 68 to link 69. Link 69 is interpivoted as at 70 to the window frame 17. It will be noted that the links 61, 63 are located between lever portions 46 and slider member 16 and disposed within chamber 31.

It will be further observed that the links 67, 69 are interposed between lever portions 44 and the sash frame 25 and within chamber 31.

Means is provided to lock the window sash to the sliders in vertical position. To this end each slider member is formed adjacent the upper end thereof with a horizontal recess or blind opening 80. Received within each recess is a cup 81 formed at its front end with a ball seat 82. Seated on the ball seat 82 is a ball 83. Interposed between the ball 83 and the bottom of the cup is a coil compression spring 84 to retain the ball 83 on the seat 82. Attached to the outer surfaces and upper corner portions of the sash frame are socket members 85 adapted to receive the portion of the ball which projects from the socket 81. It will thus be understood that when the window sash is in vertical position, the balls 83 will snap into the sockets 85 to retain the window sash in vertical position.

If it is desired to move the window sash to an inclined position for ventilating purposes, the top of the sash frame 25 need merely be grasped and the window sash pulled inwardly to release the balls 83 from the sockets 85. The window sash

17 together with the levers 40 will then swing about the pivot pins to substantially a 45° angle and will be supported in such position by the links 61, 63. If it is desired to thereafter move the window sash to a horizontal position as shown in Fig. 4, it is merely necessary to grasp the fingers 47 of the levers 40 and pull the levers upwardly to release the window sash for swinging movement relative to the levers. The window sash can then be moved down to horizontal position and will be supported in such position by the links 67, 69.

The window sash can be moved back to inclined position and the levers 40 are thereafter then moved downwardly to engage pins 55 with the slots 50 and also so that the slot portions 43 will engage the webs 22b of the pivot pins 22. From inclined position, the window sash can very easily be moved back to vertical position where the balls 83 will again snap into the sockets 85.

In Fig. 9 there is shown a modified construction which permits adjusting the window to angles other than 45° and horizontal. As shown in Fig. 9, pivoted to the sliders 16 as at 60a are links 61a formed with longitudinal slots 61b. Pivoted to the levers 40 as at 64a are links 62a formed with longitudinal slots 62b. Extending through the crossing slots 61b and 62b is a bolt 62c provided with a wing nut 62d. It will now be understood that the lever 40 may be moved to various angles and the links may be fixed in desired position by means of the wing nut 62d.

It will now be seen that I have provided a construction whereby a pivoted window sash can be tilted inwardly to an acute angle for ventilating purposes, and also provided means whereby the window sash can be maintained in such position. Said means comprising two sets of movably connected links. One set being movably attached to a shiftable bar which is releasably attached at its upper and to the upper end of the window sash at one side edge thereof, and the other set being movably attached to a like bar, similarly attached to the opposite edge of the window. Two additional sets of movably connected links are, likewise, attached to the bars and the opposite side edges of the window sash whereby said window sash can be further tilted inwardly beyond the acute angle to a substantially horizontal position when said bars are released from the window. The additional sets of links support the window sash in a substantially horizontal position, primarily, for cleansing purposes, since it is self evident that the ventilation would ordinarily be much increased by a wide open window.

I have also provided means whereby both the levers and both sets of links can be neatly and securely housed within my window when the window is closed.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:

1. A window construction, said construction comprising; a pair of vertical slidable members,

a window sash disposed between said members, pivot pins connecting the window sash at its lower end to the lower ends of said members, a pair of levers each one of said pair being normally located between the window sash and one of said members, each of said levers being mounted adjacent its lower end on one of said pivot pins, cooperating, releasable interengaging means on the upper ends of both of said levers and said window sash whereby said levers and window sash may be tilted inwardly as a unit to define an acute angle with said members, a pair of sets of links each set comprising a pair of links movably connected together end to end, one end link of each pair of links being pivotally connected respectively to said levers intermediate the ends of said levers, each opposite end link of each pair of links being pivotally connected respectively to said members intermediate the ends of said members whereby said levers and window sash as a unit may be maintained at an acute angle relative to said members for ventilating purposes, a second pair of sets of links each set comprising a pair of links movably connected together end to end, one end link of each set being respectively pivotally connected to the levers intermediate the ends thereof, each opposite end link of each pair being respectively pivotally connected to the window sash intermediate the ends thereof whereby said window sash may be supported in substantially a horizontal position primarily for cleansing purposes while the upper end of said window sash is released from the upper ends of said lever.

2. The construction set forth in claim 1, in which each lever is provided with an offset in its central portion, said window sash having a rabbet in each of its vertical outside portions and in the rearmost part thereof defining housings receiving said levers, the offset of each lever in combination with said rabbeted portions defining in each instance upper and lower compartments receiving respectively said sets of links which are movably connected respectively to said levers.

3. A window construction comprising a pair of vertical slidable members, a window sash disposed between said members, pivotal means connecting the window sash at its lower end to the lower ends of said members, a pair of levers pivotally connected at their lower ends to said members and the window sash at the lower ends thereof, a pair of movably connected links connecting each lever to one of said members intermediate the ends of both of said levers and both of said members, whereby said levers and said window sash may be tilted inwardly as a unit and be supported at an acute angle to said members for ventilating purposes, cooperating, releasable interengaging means on the upper ends of both of said levers and said window sash, a second pair of links each pair being movably connected together and also being movably connected to said window sash and to said levers intermediate the ends of said window sash and both of said levers whereby said window sash when released from said levers may be moved to and supported in substantially a horizontal position primarily for cleansing purposes of the outside of said window sash.

4. The construction set forth in claim 3, in which each lever is provided with an offset portion centrally located therein and extending transversely thereof, said window sash having a rabbet in each of its vertical outside portions and in the rearmost part thereof defining a housing

receiving said levers, the offset of each lever in combination with said rabbeted portions defining in each instance upper and lower compartments receiving respectively said pairs of links.

5. A window construction, said window construction comprising a pair of parallel symmetrically disposed vertical coextensive slider members, a window sash of the same height as said members, each member having a longitudinal rabbet 10 therein located on their adjacent edges and on the inner sides thereof defining a laterally extending flange and a forwardly extending flange, said laterally extending flanges constituting window sash stops, a window sash disposed between the major portions of said members and normally abutting said stops, horizontal pivot pins fixed to the window sash adjacent the lower end thereof and rotatably engaging said members adjacent their lower ends for pivotally connecting the window sash with the members, each pivot pin having a flattened portion located centrally thereof, said flattened portion constituting a web located between the window sash and its adjacent member, a lever movably mounted between each member and the window sash, said lever having an inverted keyhole slot in its lower end portion, each lever having cooperating means thereon and on said window sash for mounting said lever for limited longitudinal movement on said window sash and on said pivot pin whereby each lever in its lowermost position engages the web and relative rotation between the window sash and levers is prevented, each lever in its uppermost position being free to rotate about said web, each 20 lever being movably connected to its adjacent slider member by a pair of movably connected links whereby said window sash is free to swing forwardly to an acute angle with said members and is retained in such position for ventilating purposes by said pair of links, each pair of links being connected to the members and to the levers intermediate the ends of the same, a second pair of movably connected links, movably connected to said window sash and to each lever at positions intermediate to the ends thereof, whereby 30 when the upper ends of said lever are released from the window sash said window sash will be free to swing farther forwardly from the acute angle to a substantially horizontal position primarily for cleansing purposes, said last named links supporting the window sash in its last named position.
6. A window construction comprising a pair of parallel symmetrically disposed vertically coextensive slider members, a window sash of the same height as said members and received between the same, horizontal pivot pins fixed to the window and rotatably engaging said members for pivotally interconnecting the lower end 40 of said window sash with the lower ends of said members, each pivot pin having a flattened portion located between the window sash and its adjacent member, a lever movably mounted on each pin and located between the window sash and each one of the slider members, means on each lever and on the window sash releasably connecting the same for limited longitudinal movement, said lever having an inverted keyhole slot in the lower end portion thereof whereby each lever in its lowermost position engages said flattened portion of each pin whereby relative rotation of the lever is prevented and in its uppermost position is free to rotate about said flattened portion of its pin, links interconnecting each 50 lever with one of its adjacent side members, a

second group of links respectively movably connecting said window sash with said levers intermediate their ends, said levers each having an intermediate offset portion, the links which interconnect the levers with the window sash being located between the levers and the window sash and below said offset, and the links which interconnect the levers and the members being located between the levers and the members and above said offset when the window sash is closed.

7. A window construction comprising a pair of vertical slidable members, a window sash disposed between said members, pivotal means connecting the window sash at its lower end to the lower end of said members, a pair of levers pivotally connected at their lower ends to said members and the window sash at the lower ends thereof, means movably connected to each lever and to one of said members intermediate the ends of both of said levers and both of said members and interconnecting the same, permitting tilting of said levers and said window sash inwardly as a unit, and supporting the same at an acute angle to said members for ventilation purposes, cooperating, releasably interengaging means on the upper ends of both of said levers

10

15

20

25

and said window sash, means movably connected to said window sash and to said levers and interconnecting the same intermediate the end of said window sash and both of said levers, permitting said window sash when released from said levers to be moved to substantially a horizontal position and supporting said window sash in such position purely for cleansing purposes of the outside of said window sash.
